UNITED STATES PATENT OFFICE

2,367,271

SLED

Arne Habostad, North Tacoma, Wash.

Application June 17, 1943, Serial No. 491,191

3 Claims. (Cl. 280—11.37)

My invention relates to improvements in sleds for use more particularly by trappers, ski-troopers, and the like, for transporting load packs over frozen trails, rivers, and snow-covered ground.

The primary object of my invention is to provide a light-weight, strong sled utilizing a pair of skis as runners, and ski poles as load supporting devices and pusher members, and which is adapted to be easily and quickly taken apart when it is desired to use the skis and ski poles as such.

Another object is to provide a sled characterized and for the purposes as above set forth, and which is adjustable as to width, involves a minimum number of parts in excess of the skis and ski poles, which may be easily packed and carried on the person using the skis and poles in the usual manner, and which is safe and forms inexpensive equipment for transporting heavy loads.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a view in side elevation illustrating my improved sled in its preferred embodiment, Figure 2 is a view in top plan,

Figure 3 is a view in transverse section taken on the line 3—3 of Figure 2,

Figure 4 is a view in perspective of the bridging frame,

Figure 5 is a view in side elevation of a modified embodiment of my improved sled,

Figure 6 is a view in top plan of the same, and

Figure 7 is a detail view in vertical transverse section taken on the line 7—7 of Figure 5.

Referring to the drawings by numerals, and first to Figures 1 to 4 thereof, in the preferred embodiment of my invention, a pair of the usual skis 1, 2 are detachably connected together in side-by-side, parallel, laterally spaced relation to form runners and by means of a skeleton bridging frame 3 extending across the tops of the skis 1, 2 in upright position, in substantially the transverse center of the skis, and a tie bar 4 extending across the tops of the toes 5 of said skis.

The bridging frame 3 comprises a flat base bar 6 of suitable light metal providing end portions 7 extending flat across the tops of the skis 1, 2

and adapted to project beyond the side edges of said skis for a short distance and an upwardly bowed center portion 8 between said end portions 7. A pair of side uprights 9 arise from the end portions 7 directly over the skis 1, 2 and which are of angle iron form, and suitable metal, with one flange 10 facing forwardly and the upper ends of said flanges concaved to form sockets for a purpose presently seen. The uprights 9 are formed, preferably, integrally with the end portions 7. A pair of diagonal brace rods 11 extend between the upper ends of the flanges 10, in a common plane with said flanges, to the upper face of the bowed portion 8, and are crossed in the vertical center of the frame 3 to provide a crotch 12 below the concave upper ends 10' of the uprights 9. The brace rods 11 are connected, as by welding, not shown, to the flanges 10 and to the bowed portion 8. The end portions 7 of the brace bar 6 are detachably attached to the side edges of the skis 1, 2 as follows:

Each ski 1, 2 is provided with a pair of pins 13 extending from the side edges thereof, respectively, laterally, and in substantially the transverse center of the skis, and which are formed with down-turned outer ends. A pair of eye bolts 14 are looped over each pair of pins 13 and extended upwardly through the overlying end portions 7 of said bar 6 with wing nuts 15 thereon bearing against said end portions. The eye bolts 14 extend through longitudinal slots 16 in the end portions 7 of the base bar 6 to provide for adjusting the skis 1, 2 laterally, relatively, so that the width of the sled may be varied.

The tie bar 4 is detachably connected to the toes 5 of the skis 1, 2 by upwardly extending bolts 17 passing through slots 18 in said bar so that the skis 1, 2 are laterally adjustable at the toe ends thereof, also. The heads 20 of the bolts 17 may be countersunk in the toes 5 of the skis, and the bolts provided with jam nuts, as at 21. A pair of eye bolts, or screws, 22 extend upwardly from each ski forwardly of the frame 6. A pair of side brace bears 23 extend downwardly and forwardly from the sides of the uprights 9 to said eye bolts 22 and are provided with front end hooks 24 for insertion through said eye bolts 22. The rear ends of the brace bars 23 are longitudinally slotted, as at 25 for the extension therethrough of bolts 26 passed through suitable bolt holes, as at 27, in said uprights 9, the bolts 26 being also equipped with wing nuts 28.

Each eye bolt 22 carries a ring 29 swivelly dis-

posed in the eye thereof, and for the insertion of the point of the usual ski poles 30 therein. A pair of ski poles 30 may be inserted in the rings 29 with their points bearing on the skis 1 and 2, and the poles slanting upwardly and rearwardly and resting in the concave ends 10' of the uprights 9 so that said poles provide pusher members for propelling the sled and also load pack sustaining members for supporting a load pack, as at 31, interposed between the poles and resting in part in the crotch 12.

The uprights 9 are provided with upper end slots 32 through which a tie rope 33 may be extended to tie the load pack 31 onto the poles 30 and in the crotch 12.

In the modified embodiment of the invention shown in Figures 5, 6, and 7, a pair of front and rear bridging frames 35, 36, similar to the frame 3, are utilized to connect the pair of skis 37, 38 together, one frame being arranged between the transverse centers and toes of the skis, and the other adjacent to the rear ends of said skis. Side brace bars 39, similar to brace bars 23 extend between the side uprights 40 of said frames to eye bolts 41 on the skis arranged intermediate said frames. In this embodiment of the invention, the concave sockets 42 in the upper ends of said uprights 40 provide rests for a pair of longitudinally extending side poles 43, and the crossed diagonal brace rods 44, similar to brace rods 11, serve to support in the crotches thereof a longitudinally extending lower center pole 45. As will be seen, by reference to Figures 5 and 6, the poles 43 and 45 form a skeleton bed which may be utilized to support a load pack in elevated position above the skis 37, 38.

As shown in Figure 7, in the modified embodiment of my invention, the base bars 46 of the frames 35, 36, have their ends detachably attached to the skis 37, 38 by a pair of bolts 47, the ends of which are countersunk in the bottom of the skis, and which are equipped with jam nuts 48 countersunk in the tops of the skis, and with wing nuts 49 for bearing against said ends. One bolt 47 of each pair extends through a slot 50 in the related ends of the base bar 46, said slots serving to compensate for manufacturing variations in spacing of the pairs of bolts 47 in the skis.

As will be apparent, by detaching the frame 9, tie bar 4, ski poles 30, and brace bars 23, in the preferred embodiment of the invention, the skis 1, 2 may be rendered available for use as such, together with the poles 30, and the detached parts, together with the eye bolts 14, wing nuts 15, eye bolts 26, wing nuts 28, and the wing nuts 12, may be packed in a small bundle for carrying as a shoulder pack. By detaching the frames 35, 36, and other parts connecting the skis 37, 38 together in the modified embodiment of the invention, such parts may be compactly arranged within a small space for storage to permit the use of the skis and ski poles as such.

The foregoing will, it is believed, suffice to impart a clear understanding of my invention without further explanation.

Manifestly the invention, as described, is susceptible of modification without departing from the inventive concept, and right is herein reserved to such modifications as fall within the scope of the appended claims.

What I claim is:

10. 1. A sled comprising a pair of skis, means to connect said pair of skis together in laterally spaced parallel relation comprising a skeleton frame embodying a flat upwardly bowed base bar bridging said pair and having ends extending across the top of said skis, respectively, a pair of uprights arising from said ends of the base bar, and having concave socket forming upper ends, a pair of keeper rings swiveled on said skis, respectively, in advance of said uprights, and a pair of poles supported by said uprights in inclined positions with intermediate portions resting in said sockets and ends thereof inserted in said rings, said poles serving as pusher members and for sustaining a load pack in elevated position.
15. 2. A sled comprising a pair of skis, means to connect said pair of skis together in laterally spaced parallel relation comprising a skeleton frame embodying a flat upwardly bowed base bar bridging said pair and having ends extending across the tops of said skis, respectively, a pair of uprights arising from said ends of the base bar, and having concave socket forming upper ends, a pair of keeper rings swiveled on said skis, respectively, in advance of said uprights, a pair of poles supported by said uprights in inclined positions with intermediate portions resting in said sockets and ends thereof inserted in said rings, said poles serving as pusher members and for sustaining a load pack in elevated position.
20. 3. A sled comprising a pair of skis, means to connect said pair of skis together in laterally spaced parallel relation comprising a skeleton frame embodying a flat upwardly bowed base bar bridging said pair and having ends extending across the tops of said skis, respectively, a pair of uprights arising from said ends of the base bar, and having concave socket forming upper ends, a pair of keeper rings swiveled on said skis, respectively, in advance of said uprights, a pair of poles supported by said uprights in inclined positions with intermediate portions resting in said sockets and ends thereof inserted in said rings, said poles serving as pusher members and for sustaining a load pack in elevated position, and means to bind a load pack on said poles and said poles to said uprights.
25. 4. A sled comprising a pair of skis, means to connect said pair of skis together in laterally spaced parallel relation comprising a skeleton frame embodying a flat upwardly bowed base bar bridging said pair and having ends extending across the tops of said skis, respectively, a pair of uprights arising from said ends of the base bar, and having concave socket forming upper ends, a pair of keeper rings swiveled on said skis, respectively, in advance of said uprights, a pair of poles supported by said uprights in inclined positions with intermediate portions resting in said sockets and ends thereof inserted in said rings, said poles serving as pusher members and for sustaining a load pack in elevated position, and a pair of brace bars for said uprights inclining downwardly from the same to said skis and detachably attached to the uprights and skis.

ARNE HABOSTAD.
